UNITED STATES PATENT OFFICE.

JAMES M. WALSH, OF MILWAUKEE, WISCONSIN, ASSIGNOR TO JAMES M. WALSH CO.,
OF MILWAUKEE, WISCONSIN, A CORPORATION OF DELAWARE.

BRIDLE.

Application filed May 22, 1924. Serial No. 715,121.

This invention relates to improvements in bridles and more particularly to means for adjusting the bit.

It is one of the objects of the present invention to provide a novel form of connector which will permit adjustments between the bit and head-stall of a bridle but which eliminates the use of apertured straps which tend to weaken a bridle.

10 A further object of the invention is to provide a bridle in which the bit rings are adjustably carried by means of chains instead of straps as commonly used.

15 A further object of the invention is to provide a connector for bridles which is equally well adapted to receive either link chains or adjustable straps if required.

20 A further object of the invention is to provide a bridle which will be comfortable to an animal wearing the same.

25 A further object of the invention is to provide a bridle which is of very simple construction, is strong and durable, is inexpensive to manufacture, and is well adapted for the purposes described.

With the above and other objects in view, the invention consists of the improved bridle and its parts and combinations as set forth in the claims, and all equivalents thereof.

30 In the accompanying drawing in which the same reference characters indicate the same parts in all of the views:

Fig. 1 is a fragmentary view of the head-stall of a bridle provided with the improved connector, the bit ring and bit being adjustably connected thereto; and

Fig. 2 is a sectional view taken on line 2-2 of Fig. 1.

Referring now more particularly to the drawing it will be seen that the numeral 5 indicates the improved bridle connector. The connector is formed of a metallic frame 6 substantially square in form with an integral angularly bent portion 7. A transverse portion 8 divides the portions 6 and 7 and provides a main opening 9 and an auxiliary opening or slot 10. A hook 11 is formed integrally with the mid portion of the transverse member 8, said hook being curved as clearly shown in Fig. 2 with the end 12 thereof extending through the opening 9 and slightly beyond the plane of the frame 6.

The connector is adapted to have attached thereto straps 13 and 14 forming part of the

head-stall of a bridle and a chain 15 is adjustably carried by the hook 11, as shown. The lower end portion of the chain 15 carries a bit ring 16 to which is secured one end of a bit 17.

Obviously, the connector 5 permits adjustments of the chain 15 to lower or raise the bit 17. Adjustments of the chain are attained by engaging the hook 11 with any of the links of the chain to lengthen or shorten the same. To engage a link with the hook, it is merely necessary to pass the link through the opening 9 and drop the same over the end 12 of the hook, as shown in dotted lines in Fig. 2. The chain will then assume the position on the hook shown in full lines in Figs. 1 and 2, and will be securely retained in place.

To prevent the hook 11 from projecting, so as to rub or become uncomfortable to an animal wearing the bridle, a leather flap 18 is provided. Said flap is sewed to the head-stall members 13 and 14 and normally is positioned as shown in full lines, in Fig. 2. However, when it is desired to adjust the bit, the flap 18 may be bent outwardly, as shown in dotted lines in Fig. 2, to expose the hook 11.

It may happen that a person may desire to substitute an adjustable strap to attach an unusual bit to the head-stall, for the chain 15, and to that end, the connector is formed with the portion 7. When a strap is used, it is passed through the slot 10 and about the portion 7.

From the foregoing description it will be seen that the improved bridle is of very simple and novel construction, and is well adapted for the purpose set forth.

What I claim as my invention is:

As a new article of manufacture, a connector consisting of side portions, end portions, a transverse bar connecting the sides and forming a strap loop, said side and end portions and transverse bar being in the same plane and a non-yieldable curved hook portion extending outwardly from the medial part of said transverse bar and then curving inwardly through the plane of said side portions and terminating beyond the plane of said side portions.

In testimony whereof, I affix my signature.

JAMES M. WALSH.
